UNITED STATES PATENT OFFICE

SAMUEL RUBEN, OF NEW YORK, N. Y., ASSIGNOR TO RUBEN TUBE COMPANY, A CORPORATION OF DELAWARE

ELECTRON DISCHARGE TUBE

Application filed July 11, 1927. Serial No. 205,024.

This invention relates to an electron discharge tube and particularly it relates to an electron discharge tube having an indirectly heated electron emission element. Its object is the provision of a thermionic discharge device adapted to function when the emission element is heated by conduction from an element through which a heating current is conducted, with practically no interruption of the electron stream due to the cycles of a heating current.

In devices of this kind in the prior art two general types of cathode elements are employed: those dependent upon conduction from the heater element through an electrical insulating body or cover to the emitting surface, and those employing thermal radiation from an incandescent filament to the adjacent emission element, usually in the form of an oxide coated tube. In both devices there is an appreciable thermal lag in the response from the emitter surface when the tube is connected in the heater circuit.

In the tube of my invention the elements employed reduce the lag factor to a negligible value, and the tube functions with substantially no hum.

To accomplish this result, for the heater element I use a conductor of low electrical resistance, such as a tungsten wire with a cross section so large that the current cycles have little response in thermal variation, and that only a low voltage is required for operation; this signifies low transverse electrical field modulation effects. Upon the low resistance element is helically wound a relatively high resistance element, such as tantalum wire or a compound of nickel and chromium, through which, because of its higher specific resistance and the high contact resistance of the tantalum wire, a very small amount of the heating current is conducted, this element, however, having a high thermal conduction. For the electron emission element is preferably employed a high emission body, such as a thorated tungsten wire, or a platinum wire coated with a high emission oxide, such as a mixture of strontium and barium oxides, this wire being wound upon the higher resistance wire. The electrical emis-

sion element in this form is wound as a helix about the high and low resistance elements, but contacting only with the latter element, with which it contacts tangentially. The coated platinum wire is preferred because of its low operating temperature.

I find that the high resistance wire around the heater base is substantially the electrical equivalent of the insulation shells of lava or quartz of the devices of the prior art, but lacking the thermal lag of the latter due to its high thermal conductivity.

To provide for minimum potential differences along the emitter, this element wound as described, about the other elements, is tapped at a point substantially equidistant from the ends, along the long axis of the assembled heater-cathode elements instead of the end, for its connection in the cathode-anode circuit.

For a better understanding of the invention reference is made to the accompanying drawings, illustrative of one embodiment thereof, in which, Fig. 1 shows the cathode with its several members, Fig. 2 represents a diagrammatic view of an evacuated tube containing a cathode and its several members, a grid and an anode, together with the connecting electrical circuits, and Fig. 3 represents a plan section of the tube at 3—3. Fig. 4 is a detail view of the elements illustrated by Fig. 1. In the several figures the corresponding elements are represented by the same numerals.

Referring more particularly to Fig. 1, 1 represents a tungsten wire heater element, having helically wound around its tantalum wire 2 and helically wound over the latter the emitter, a thorated tungsten wire 3, 3_a representing a lead from the emitter to the external cathode-anode circuit. Referring more particularly to Fig. 2, the heater element 1 is supported by conducting wires 1_a, 1_b and 1_c, connected by terminals 1_c and 1_a through transformer T in the circuit of generator G. Tantalum wire is not connected in any circuit, serving only as an electrical resistance between the heater and emitter elements and as a thermal conductor to contacting emitter 3, which is wound upon the

- tantalum wire, through which a negligible amount of the heating current is conducted to the emitter. The latter is connected by lead 3_a and support 3_b by terminal 3_c in the 5 cathode-anode circuit in which are potential sources B and telephone receiver R. Mounted on the supports 4_a and 4_b is grid 4 having a terminal at 4_c for connection in the input circuit, in which I represents the input coil.
- 10 Surrounding the cylindrical grid 4, is anode plate 5, shown partly cut away, mounted on supports 5_a and 5_b, the former connected by terminal 5_c in the cathode-anode circuit.
- 15 The operation of a tube having these elements is the same as that of the commonly known three-element vacuum tube, except that the filament is heated to emission temperature by conduction from a distinct heater element. There is practically no noticeable 20 hum in the receiving circuit due to the cycles of any alternating current heating current.

High resistance materials, other than those named as composing the body separating the emitter from the heater, may be satisfactorily used. For instance, in this capacity such electrically conductive yet high resistance materials as carbon, graphite or a mixture of cotton and colloidal silver can be so employed. The mixture of cotton and colloidal silver should first be heated to convert the cotton into carbon, this combination having a fair thermal conduction and a high electrical resistance. The emitter may also satisfactorily be cylindrical in form.

35 What I claim is:

1. A vacuum tube having an anode, a grid, a heater element composed of a refractory metal, an electrically conductive metal body wound upon and in surface contact with 40 and having a relatively higher specific resistance than the heater element, and a metal cathode of relatively higher electron emissivity wound upon and in surface contact with the high resistance body.
- 45 2. A vacuum tube having an anode, a grid, a heater element for the direct conduction therethrough of a heating current, an electrically conducting metal body in surface contact with and having a relatively higher specific resistance and thermal conductivity 50 than the heater element and an indirectly heated metal electron emission element wound upon and in tangential contact with the higher resistance body, said emission element being connected with the anode by a lead from a point along the long axis of the emission element between its two ends.
- 55 3. A vacuum tube having an anode, a grid, a heater element composed of tungsten and an electrically conductive metal body in surface contact with and having a relatively higher specific resistance than the heater element, and an indirectly heated cathode wound upon and tangentially in contact with the higher resistance body, and connected

from a point along the long axis of the emission element between its ends with the anode.

4. A vacuum tube having an anode, a grid and a cathode, the latter comprising a heater element, a tantalum body wound upon and in surface contact with the heater element

70

and another metal body of relatively higher emissivity wound upon and tangentially in surface contact with the tantalum body.

5. A vacuum tube having an anode, a grid and a cathode, the latter comprising a heater element composed of tungsten, wound upon a tantalum body in surface contact with the heater element and another metal body of

75

relatively higher emissivity wound upon and tangentially in surface contact with the tantalum body.

80

Signed at the city of New York in the county of New York and State of New York this 8th day of July, A. D. 1927.
